UNITED STATES PATENT OFFICE.

UMBERTO PIAGNERI, OF SAN FRANCISCO, CALIFORNIA.

LOCK.

1,319,357.

Specification of Letters Patent.

Patented Oct. 21, 1919.

Application filed May 16, 1917. Serial No. 168,954.

To all whom it may concern:

Be it known that I, UMBERTO PIAGNERI, a subject of the King of Italy, residing at the city and county of San Francisco and State 5 of California, have invented new and useful Improvements in Locks, of which the following is a specification.

This invention relates to an improved permutation lock, particularly adapted to 10 be applied to doors, but may be used for other purposes.

The object of this invention is to simplify and improve the construction and operation of a lock of this character.

15 In its present form the invention contemplates a locking bolt adapted to be advanced and retracted by a rotatable movement, actuating means for said bolt, which means is in the form of a pivoted arm or arms on 20 one or both sides of the door fitted with a gear segment to mesh with a pinion for turning the bolt, and suitable permutation locking mechanism for retaining the actuating arm in position where the bolt will be 25 advanced.

Referring to the drawings which form a part of this specification:

Figure 1 is a front elevation of the lock as applied to a door.

30 Fig. 2 is a rear elevation of the lock shown in Fig. 1.

Fig. 3 is a side view of said lock.

Fig. 4 is a sectional view of said lock, taken on the line 4—4 of Fig. 3, showing 35 the lock in unlocked position.

Fig. 5 is a sectional view of the lock taken on line 5—5 of Fig. 4, with the lock in unlocked position.

40 Fig. 6 is a sectional view, similar to Fig. 4, showing the lock in locked position.

Fig. 7 is a view similar to Fig. 5, showing the lock in locked position.

Fig. 8 is a sectional view taken on line 45 8—8 of Fig. 4.

Fig. 9 is a fragmentary view of the structure for causing the locking bolts to move into or out of locking position.

Fig. 10 is a longitudinal sectional view 50 of the combination locking mechanism.

Fig. 11 is an end view of the combination latch sleeves.

Fig. 12 is a cross sectional view showing certain parts taken on the line 12 of Fig. 10.

55 Fig. 13 is a cross sectional view taken on the line 13 of Fig. 10.

Fig. 14 is a cross sectional view taken on line 14 of Fig. 10.

Fig. 15 is a cross sectional view taken on line 15 of Fig. 10.

The various parts of the lock are mounted in a frame 1. As shown in Figs. 1 and 2, when the lock is applied to a door, the frame 1 is fitted in and secured to the swinging edge of the door. The frame has a front wall 2, a rear wall 3, an inner wall 4 and a wall 5 which aligns with the edge of the door.

The walls 4 and 5 are provided, respectively, with apertures 6—7 and 8—9, through which extend locking bolts 10 and 11. The wall 4 is also provided with a socket 12 and the wall 5 is provided with an aperture 13 to receive a locking bolt 14, intermediate the bolts 10 and 11. The intermediate bolt 14 is turnably secured in a connecting member 15, which connects the three locking bolts 10, 11 and 14 so that they will move together. A pinion 16 is secured on the bolt 14, between the connecting member 15 and the wall 4, and is adapted to mesh with segmental gears 17 and 18 on arms 19 and 20, respectively, which arms are pivoted at 21 and 22 on the front and rear walls of the lock frame. The front wall of the frame is provided with grooves 23, 24 and 25 in which the arm 19 is adapted normally to rest. The rear wall 3 is provided with grooves 26, 27 and 28 in which the arm 20 is adapted normally to rest.

90 The socket 12 is provided with a helical slot 30 which receives a pin 31 carried by bolt 14, so that when the bolt 14 is rotated by the meshing of the segmental gears 17 and 18 with the pinion 16, upon turning the arms 19 or 20, the engagement of said pin 31 with said slot will cause the bolt 14 and the bolts 10 and 11 to move longitudinally into locking or unlocking position according to the direction of rotation of the pin and its location in the slot.

100 A spring latch 35 is reciprocally mounted in the outer end of the bolt 14 for engaging a lock plate 36 secured to the door jamb to hold the door closed while unlocked. Lugs 37 and 38 are provided on the pivot ends of 105 the arms 19 and 20 for engaging the face of the pinion 16 to lock the locking bolts 10, 11 and 14 in locking position, as will be herein-after more particularly set forth. A spring latch 40 is provided in the outer end of the 110

arm 20 for engaging openings 41 and 42 in the wall 3 to hold the arm in its upper or lower position. A pin 43 projects from the latch through a slot 44 in the arm for disengaging the latch. A permutation lock is provided to lock the arm 19 in its upper position, in which position of the arm the locking bolts have been moved forward by the engagement of the segmental gear 17 with pinion 16, and the lug 37 is adjacent to the rear face of pinion 16, whereby the locking bolts are locked in locking position.

The permutation lock comprises, generally, a latch engaging lug 50, secured with 15 in the upper groove 25 to the wall 2, a pair of spring latches 51 arranged on opposite sides of the outer end of the arm 19 adapted to engage the lug 50, and a permutation mechanism 52 for the operation of each 20 latch. The lug 50 has two inclined cams 55 and two shoulders 56, respectively, for engaging the latches 51 in the manner and for the purpose to be more fully described. As both latches 51 and both permutation 25 mechanisms 52 are the same, the following description of one will apply to both.

The latch is formed with an outer sleeve 60, reciprocally mounted within the outer end of the arm 19 and an inner sleeve 61 30 turnably mounted with said outer sleeve and reciprocal therewith. A plunger 62 extends into the outward end of the sleeve 61 and has a reduced end 63 and a shoulder 64, said reduced end fitting within an opening 65 35 in the end wall of a cap 66 and said shoulder engaging the inner face of said wall. A spring 68 fits within the sleeve 61 and bears against the inner end wall 67 of said sleeve and against the inner end of said plunger. 40 A separable tumbler center 70 fits on the outer end of the latch sleeve 60 and a similar tumbler center 80 fits on the outer end of the sleeve 61. These tumbler centers are formed with grooves 71 and 81 to receive 45 lugs 72 and 82 on the respective sleeves 60 and 61, whereby said centers are keyed to the sleeves for relative axial movement.

In their peripheries at their outer ends, the tumbler centers 70 and 80 are provided 50 with a plurality of notches 73 and 83 equally spaced apart and adapted to receive the respective inwardly extending pairs of lugs 74 and 84 of the permutation tumblers 75 and 85 which fit over the tumbler centers 70 and 80. The cap 66 fits over the permutation tumblers and its inner end screws on the outer end of the arm 19 against a shoulder 86 on said arm so that the permutation tumblers and the tumbler centers will fit closely 55 80. The lug 72 is adapted to engage the outer end of the arm 19 to prevent the latch sleeve 60 from coming out of 60 but in turning relation between the outer end of said arm and the inner face of the end wall of cap 66. The lug 72 is adapted to 65 engage the outer end of the arm 19 to prevent the latch sleeve 60 from coming out of the tumbler center 70.

The inner end of the latch sleeve 60 has an internal annular flange 87 against which the inner end of the latch sleeve 61 abuts and is retained within the sleeve 60 against the action of the spring 68. The shoulders 56 70 are adapted to engage the inner surface of the internal annular sleeve flange 87 and the inner surface of the latch sleeve 61 to hold the arm 19 and the lock in locking position. Notches 88 and 89 respectively, are provided 75 in the inner end of the latch sleeves 60 and 61 which are adapted to register with each other to permit the cam 55 to pass therethrough whereby the arm and lock are unlocked. Characters such as 0 to 9 may be 80 placed on the periphery of the permutation tumblers to indicate when the latch sleeves have been turned so that the notches 88 and 89 register and are in position to permit the latch lug cam 55 to pass therethrough to unlock the arm and the lock. The periphery of the permutation tumblers may be roughened to facilitate turning of the same. The cap 66 is provided with an opening 90 to 85 permit access to and reading of the permutation tumblers 75 and 85. Marks 91 may be placed on the cap at the edges of the opening 90 to which marks the characters of the permutation tumblers may be brought into register by turning the tumblers for 90 establishing the combination of the lock and registration of notches 88 and 89 with cams 55 to unlock the lock. The combination of the lock may be changed by shifting the permutation tumblers 75 and 85 around the 95 tumbler centers 70 and 80 and locking the sleeve in such position by placing the lugs 74 and 84 of the tumblers 75 and 85 into the adjacent notches 73 and 83 in the centers 70 and 80, so that different numbers on 100 the tumblers will have to be brought into register with the marks 91 in order to bring the latch sleeve notches 88 and 89 properly 105 into registration so that the latch lug cams 55 may pass therethrough. The arm 19 may 110 be swung into locking position when the notches 88 and 89 do not register with the latch lug cams 55 because said cams will engage the inner end of the latch sleeve 60 and force said sleeve and sleeve 61 outwardly 115 against spring 68 until the inner surface of the flange 87 and the inner surface of the sleeve 61 pass the cam 55, whereupon the spring 68 will force the sleeves 60 and 61 inwardly and snap the flange 87 and the inner surface of the inner end of sleeve 61 120 into locking engagement with the shoulder 56 of latch lug 50.

To lock the lock the arm is swung upwardly during which operation the gear 125 segment 17 meshes with pinion 16 and turns said pinion and bolt 14; the pin 31 engages slot 30 which forces the bolt 14 and the bolts 10 and 11 outwardly through the openings in the locking plate on the door jamb into 130

locking position; the lug 37 passes behind and engages the rear surface of pinion 16 to prevent backward movement of the bolts; and the arm is then locked in its upper position 5 by the permutation lock, thus locking the lock in locked position. To unlock the lock the permutation lock is first unlocked, the arm 19 is then swung down, during which operation the gear segment 17 meshes 10 with pinion 16 and turns said pinion and bolt 14, the lug 37 is swung out of the path of said pinion so that the pinion may move inwardly; and the pin 31 engages the side of slot 30 which withdraws the bolts 14, 10 and 11 inwardly until the ends of the bolts 15 are withdrawn from the openings in the lock plate 36 into unlocked position, as shown in Fig. 4.

The arm 19 as shown in Fig. 5, is in its 20 unlocking position. If it is desired to lock the door from the inside, the latch 40 is disengaged and the arm swung down, during which operation the gear segment 18 meshes with pinion 16 and turns said pinion and bolt 14; the pin 31 engages slot 30 which forces the bolt 14 and bolts 10 and 11 outwardly through openings in the locking plate on the door jamb, into locking position; the lug 38 passes behind and engages 25 the rear surface of pinion 16 which prevents backward movement of said bolts; and the latch 40 snaps into engagement with slot 42 thus locking the lock in locked position.

30 Various other changes than those already indicated may be made in the construction and arrangement of the several parts without departing from the spirit of my invention as disclosed in the appended claims.

35 Having thus described my invention what I claim and desire to secure by Letters Patent is:

1. A lock of the character disclosed comprising a frame, a locking bolt movably 40 mounted in said frame, a pinion fixed on said bolt, an arm pivoted to said frame, a gear on said arm adapted to mesh with said pinion, a pin on said bolt, a cam on said frame for engaging said pin to force said 45 bolt into locking position when said pinion and bolt are rotated by the gear on said arm, means on said arm for engaging said pinion to prevent backward movement of the bolt when in locking position, and means for locking said arm in position with said means engaging said pinion.

2. A door lock of the character disclosed comprising a frame, a locking bolt movably mounted in said frame, a pinion on the bolt, 50 an arm pivoted to said frame, a gear on said arm normally out of but adapted to mesh with said pinion, a pin on said bolt, a cam on said frame for engaging said pin to force said bolt into locking engagement with said plate, when the pinion and bolt are rotated

5 by the gear on said arm, means on said arm for engaging said pinion when the latter is disengaged from the gear to prevent backward movement of the bolt when in locking position and means for locking said arm in 70 position with said means engaging said pinion.

3. A lock of the character disclosed comprising a frame, a locking bolt movably mounted in said frame, an arm, means actuated by said arm for forcing said bolt into locking position, means independent of the first means and actuated by said arm for preventing withdrawal of said bolt from locking position when the arm is swung into 75 locking position and means for locking said arm in locking position.

4. A lock of the character disclosed comprising a frame, a locking bolt movably mounted in said frame, an arm, means actuated by said arm for forcing said bolt into locking position, means spaced from said first means and actuated by said arm for preventing withdrawal of said bolt from locking position when the arm is swung into 80 locking position and means for locking said arm in locking position.

5. A door lock of the character disclosed comprising a frame, a locking bolt movably mounted in said frame, an arm, means actuated by said arm for forcing said bolt into locking engagement with said plate to lock the door, a locking lug independent of said means and carried by said arm for locking the bolt in locking position when the arm is 95 swung into locking position, and means for locking said arm in locking position.

6. In a lock, a bolt advanced and retracted by rotatable movement, a pinion for turning the bolt, a toothed member for meshing with 100 and turning the pinion, and means positionable by the toothed member to prevent retraction of the advanced bolt.

7. In a lock, a bolt advanced and retracted by rotatable movement, a pinion for turning 110 the bolt, and a plurality of selectively operable toothed members disposed on opposite sides of the pinion and normally out of but adapted to be moved into mesh with said pinion for rotating the latter.

8. In a lock, a body member, a bolt slidable thereon, means for sliding the bolt including a rotary member, swinging means for rotating said member to slide the bolt, said swinging means moving out of operative relation with said member subsequent to operation thereof, and means positionable by said swinging means as it moves out of operative relation with said member to arrest the bolt from movement.

9. In a lock, a frame, a locking bolt movably mounted therein, means for actuating the bolt including a swingingly mounted arm having its outer end of T-design, independently operable locking means on the 125

opposite sides of the outer end of said arm, and a keeper adapted to enter between and be engaged by said locking means to hold said arm fixed.

5. 10. A lock for doors comprising a bolt advanced and retracted by rotatable movement, a pinion for imparting rotatable movement to said bolt, and means for actuating said pinion comprising a swinging 10 arm, one on either side of the door, and a gear segment normally out of mesh with the pinion and operated by each of said arms for meshing with said pinion.

11. A lock for doors comprising a bolt 15 advanced and retracted by rotatable movement, a pinion for imparting rotatable

movement to said bolt, means for actuating said pinion comprising a swinging arm, one on either side of the door, a gear segment operated by each of said arms and meshing 20 with said pinion, and means on said arms for engaging the pinion to prevent backward movement of the bolt when in locked position.

In testimony whereof I have hereunto set 25 my hand in the presence of two subscribing witnesses.

UMBERTO PIAGNERI.
